INVENTOR,
William C. Heister,
BY R. A. Tolman,
ATTORNEY,

UNITED STATES PATENT OFFICE.

WILLIAM C. HEISTER, OF DAYTON, OHIO.

OIL-GAS BURNER.

SPECIFICATION forming part of Letters Patent No. 508,312, dated November 7, 1893.

Application filed March 18, 1893. Serial No. 466,746. (No model.)

To all whom it may concern:

Be it known that I, WILLIAM C. HEISTER, a citizen of the United States, residing at Dayton, in the county of Montgomery and State of Ohio, have invented certain new and useful Improvements in Oil-Gas Burners, of which the following is a specification, reference being had therein to the accompanying drawings.

This invention relates to certain new and useful improvements in oil-gas burners, adapted to be utilized in the consumption of hydrocarbon oils, whether heavy and crude, or light and refined; and the several peculiarities of my invention, in point of construction, and in point of organization or arrangement, will be hereinafter fully described and particularly pointed out in the claims.

In the accompanying drawings, on which like reference letters indicate corresponding parts: Figure 1, represents a side elevation of my improved burner, with parts broken away and shown in section; its application to a stove with a horizontal fire box being indicated by the dotted lines; Fig. 2, an end view of the burner detached, showing the relative positions of its several parts; and Fig. 3, a side elevation with parts also broken away and indicated in section, the application being to a stove with a vertical fire box as indicated in dotted lines.

The letter A designates the fire box of a stove of any approved style, say of the kind in which the fire box is horizontal, as in cook stoves, and sometimes in heating stoves.

Within the fire box is placed my burner, say by resting it on or attaching it to suitable supports B.

The letter C indicates the burner proper, consisting of a perforated pipe, closed at one end and connected at the other with a shell D. At or near the end of the burner which enters the said shell, I provide a chamber E from which leads a passage F, the same being formed in a bushing or plug G secured

45 within the burner. To the upper side of the shell D I connect, either by a screw thread, or integrally, an elbow H, to the other end of which is connected the vaporizing pipe, I, which extends along 50 in the same direction as the burner proper, and at its other end opens into the air outside of the stove, as by turning upward

through an elbow J. In this elbow enters the valved or cock-controlled supply pipe K leading from an oil tank L of sufficient elevation 55 to cause the oil to flow with slight pressure. The bottom of the tank may, if the location of the stove and the surroundings of the place require it, be placed about on a level with the opening where the oil supply pipe enters the 60 vaporizing pipe I. A contracted orifice M is preferred to form communication between such pipe and the supply pipe. Referring again to the other end of the vaporizing pipe I it will be seen that near it, in the elbow H, 65 in Fig. 1, and directly connected to it in Fig. 3, I provide what I term my vaporizer O, the function of which is to collect so much of the oil as passes through the pipe I without being vaporized, and there to hold it against 70 flowing into the burner, until it becomes thoroughly vaporized. Thus oil in liquid form is prevented from reaching the burner proper, except in the mere act of starting the burner, as will be hereinafter explained, and thus is 75 avoided all of those objections to oil burners which arise from the carbonaceous deposit, due to a charred condition of the solid residuum left after the volatile products have passed off, forming and accumulating in the burner 80 proper. This vaporizer consists of an outer shell and an inner elongated neck, leaving a chamber P between the shell and the neck, the latter having a passage Q. As seen in Fig. 1 the shell screws into the lower end of 85 the elbow H; as seen in Fig. 3 the shell screws onto the lower end, direct, of the vaporizing pipe I. In either case the neck extends considerably above the bottom of the chamber, and in either case the same function or functions are performed.

Into one end of the shell D is screwed or otherwise fastened a nozzle R which extends into the mixing chamber E and stands opposite the passage F. With this nozzle is connected a steam superheater S, by intermediate pipes and elbows T and U. This superheater in turn connects with another superheater V by a return W, while V in turn connects with another pipe X through a return Y, such 95 pipe X constituting a steam generator. It is supplied with water by a cock-controlled water pipe Z connecting with a water tank A' or with the city water pipes, so that the water

will pass into the pipe X of the generator under more or less pressure. A reduced orifice B' is preferred between the water pipe and the generator. It is also preferred to more or less pack the generator, with fragments of asbestos, fire brick or other non-combustible material, the natural interstices between which will form passages for the water and steam. These fragments, becoming highly heated, form a large number of heating surfaces in contact with which the water and steam are brought, and by which the water is broken up into small bodies, rendering its vaporization or conversion into steam much more readily performed. As the steam passes from the generator X into the superheaters V and S it becomes highly superheated, rendering it very dry and very hot. In this state it reaches the nozzle R, by which it is directed into the chamber E and passage F, and thence into the burner, while the vaporized oil or the oil vapors and intermixed air commingle with it in the chamber E, passage F and burner proper, the intermixture and intermingling being completed and very thorough by the time the perforations of the burner proper are reached. Thus I vaporize the oil, intermix the vapor, with air, and then intermix this mixture with steam, and so produce a fuel which gives an intense heat, is economical, and is practically free from solid matter, and devoid at the place of ignition of any capability of forming a deposit. It will also be seen that my burner will operate without the steam appliance, though the heat obtained is not so great.

By referring to Fig. 3, it will be observed, first, that I have left off the steam appliances, and secondly, that I have adapted the organization particularly for heating stoves with the usual vertical fire box. The vaporizing pipe in this figure is shown at I' in a vertical position, receiving air at its upper end, where the oil supply pipe K' enters it, the orifice M' being at a slight angle, so as to direct the oil against the side of the vaporizing pipe.

In the dotted lines at I'' in Fig. 3, I have shown the upper portion of the vaporizing pipe carried off on a horizontal, and out of one side of the stove, having an elbow J' and the oil supply pipe K'', just as shown at J and K in Fig. 1.

At the lower end of the pipe I; I screw or otherwise connect to it the vaporizer O, which is the same as the vaporizer in Fig. 1, except that the outer shell, as before observed, extends above the inner neck, and except that I prefer to make the outward flare at the lower end a little more pronounced. The operation of the burner in this figure is the same as in Fig. 1, when the steam appliances are not used in the latter. In Fig. 3, so much of the oil as is not vaporized in the pipe I' or I' I'', is received into the vaporizer O, and there fully vaporized.

In starting the burner the oil is turned on

and allowed to fill the vaporizer and slowly flow over the neck. In Fig. 3 it is ignited at the base of the vaporizer, but as soon as the vaporizer becomes hot enough, together with the vaporizing pipe, nothing but vapor passes out of the neck, being so drawn by the draft, and it burns around the base of the vaporizer, the flames licking upward and somewhat outward.

In Fig. 1 the oil must be allowed to flow until the shell D and the burner C are filled, so that it will ooze out of the perforations, for the initial lighting. As this oil burns away, the generated heat begins the vaporizing process and soon only vapor is being burned.

The entrance of the air into and through the pipes I and I' is facilitated by the partial vacuum created by the steam issuing from the nozzle R, such vacuum being essentially created in the shell D in and about the nozzle.

Having thus fully described my invention, what I claim as new, and desire to secure by Letters Patent, is—

1. In an oil-gas burner, the combination with a pipe for vaporizing oil and supplying air, an oil supply pipe discharging into it at or near one end, an opening at or near said oil supply entrance in said vaporizing pipe for the admission of air by draft, and a retort connected to the other end of said oil vaporizing pipe, said retort consisting of an outer wall and an inner neck with a space between them and a discharge opening in the neck.

2. In an oil-gas burner, the combination with the pipe I, the oil supply pipe K, the pipe I being open near the entrance of the supply pipe for the admission of air, a retort connected to the other end of the pipe I and having an elevated hollow neck, a burner proper connected to said retort and receiving fuel from it and lying substantially under the pipe I so as to heat the latter.

3. In an oil-gas burner, the combination with the pipe I, the supply pipe J connecting near one end, an air opening in the pipe I near the entrance of the pipe K, the retort O P Q attached to the other end of the pipe I, the burner C, the shell D connecting it with the retort, the nozzle R discharging into the burner and the steam generator connected to the nozzle, the pipe I in the generator lying above the burner C.

4. In an oil gas burner the following instrumentalities: a burner, a shell connected to the burner, a nozzle in the shell discharging into the burner, a generator connected with the nozzle, an oil vaporizing and air supplying pipe connecting at one end with the shell, a retort in the connection, the retort having an elevated hollow neck, an air-opening at or near the other end of said pipe and an oil supply pipe discharging into said pipe near the air-opening, the said pipe and the said generator being above said burner.

5. In an oil-gas burner, the combination with a pipe for vaporizing oil and introducing air, a shell connected to one end of said pipe, a retort in the connection having an elevated hollow neck, a nozzle in the retort, a burner connected to the shell and a generator connected to the nozzle, the retort and nozzle discharging preliminary into the shell and

their combined product passing thence into the burner.

In testimony whereof I affix my signature in presence of two witnesses.

WILLIAM C. HEISTER.
